Primary Examiner — David G Muller(74) *Attorney, Agent, or Firm* — Nixon & Vanderhye P.C.**(57) CLAIM**

The ornamental design for a humidifier tub for a humidifier for a positive airway pressure delivery device, as shown and described.

DESCRIPTION

FIG. 1 is a perspective view of a humidifier tub for a humidifier for a positive airway pressure delivery device according to our design;

FIG. 2 is a rear view thereof;

FIG. 3 is a top view thereof;

FIG. 4 is a left side view thereof; and,

FIG. 5 is a right side view thereof.

The broken lines of the humidifier tub represent environment or structure and do not form part of the claimed design.
